(57) **CLAIM**

We claim the ornamental design for a base for wireless temperature probes, as shown and described.

DESCRIPTION

FIG. 1 is a top perspective view of a base for wireless temperature probes showing the design;

FIG. 2 is a bottom perspective view thereof;

FIG. 3 is a top plan view thereof;

FIG. 4 is a bottom view thereof; and

FIG. 5 is a left side view thereof;

FIG. 6 is a right side view thereof;

FIG. 7 is a front side view thereof;

FIG. 8 is a back side view thereof; and,

FIG. 9 is a top perspective view thereof illustrating wireless temperature probes carried within the base.

The broken lines are included for the purpose of illustrating portions of the base for wireless temperature probes and form no part of the claimed design.
